US00D759126S

(12) **United States Design Patent**
Johnson et al.

(10) **Patent No.:** US D759,126 S
(45) **Date of Patent:** ** Jun. 14, 2016

(54) **DISC MOWER BLADE**

(71) Applicants: **Keith A. Johnson**, Kewaskum, WI (US);
Neal J. Stoffel, Campbellsport, WI (US)

(72) Inventors: **Keith A. Johnson**, Kewaskum, WI (US);
Neal J. Stoffel, Campbellsport, WI (US)

(73) Assignee: **Kondex Corporation**, Lomira, WI (US)

(**) Term: **14 Years**

(21) Appl. No.: **29/522,879**

(22) Filed: **Apr. 3, 2015**

Related U.S. Application Data

(63) Continuation of application No. 13/670,643, filed on Nov. 7, 2012, now abandoned.

(57) **CLAIM**

We claim the ornamental design for the disc mower blade, as shown and described.

DESCRIPTION

FIG. 1 is a top front perspective view of a disc mower blade according to a first embodiment of the present design:

FIG. 2 is a top back perspective view of the disc mower blade of FIG. 1;

FIG. 3 is a left side view of the disc mower blade of FIG. 1;

FIG. 4 is a right side view of the disc mower blade of FIG. 1;

FIG. 5 is a top view of the disc mower blade of FIG. 1;

FIG. 6 is a bottom side view of the disc mower blade of FIG. 1;

FIG. 7 is a back view of the disc mower blade of FIG. 1;

FIG. 8 is a front view of the disc mower blade of FIG. 1;

FIG. 9 is a front view of a disc mower blade according to a second embodiment of the present design;

FIG. 10 is a back view of the disc mower blade of FIG. 9;

FIG. 11 is a right side view of the disc mower blade of FIG. 9;

FIG. 12 is a left side view of the disc mower blade of FIG. 9;

FIG. 13 is a top view of the disc mower blade of FIG. 9;

FIG. 14 is a bottom view of the disc mower blade of FIG. 9;

FIG. 15 is a back view of the disc mower blade of FIG. 9; and,

FIG. 16 is a front view of the disc mower blade of FIG. 9.
